cago, Ill., a corporation of Illinois

Application July 30, 1932, Serial No. 627,025
Renewed January 12, 1938

23 Claims. (CL 60—52)

This invention relates generally to hydraulic systems of control, and more particularly to hydraulic systems and apparatus adapted for use in controlling the movement of machine parts and the like.

One of the important problems confronting machine tool designers as well as users of machine tools is that of providing the desired features of control. In other words, the ease with which an operator may control the functioning of the machine as well as the simplicity of the structural arrangement of the control mechanism is of utmost importance from the standpoint of economical shop production. Heretofore, in many instances, and this is particularly true in mechanically controlled and operated machines, complicated control mechanisms, such as clutches and the like, have been employed. In such instances, rather complicated structural design has been resorted to and it is one of the primary objects of my present invention to provide a simplified system of control for machine tools and the like in which the number of control elements is reduced to a minimum, and the ease with which an operator may control the functioning of a machine is greatly facilitated.

My invention is more particularly applicable to hydraulic systems of control and to this end I propose to provide an improved efficiently operable system wherein the use of clutches and other structures heretofore considered necessary to the efficient functioning of the machine is eliminated.

More specifically, it is an object of my present invention to provide a hydraulic actuator system in which the mere shifting of a control valve will serve to initiate the operative functioning of a pumping mechanism or to render said pumping mechanism functionally inoperative without the necessity of disconnecting said mechanism from its source of power supply.

Still another object of my invention is to provide apparatus or systems of control which are particularly applicable in instances where one pump is employed for propelling a machine part at a feeding rate and another pump is employed for propelling said part at a rapid rate, and to this end I propose to provide means responsive to the movement of a main control valve for controlling the functioning of one of the pumps without affecting the functioning of the other pump.

Still more specifically, my invention contemplates the provision of means shiftable in response to the slight movement of a main control valve for operatively connecting a pump, such as

one of the above mentioned pumps, with an actuator, such as an actuator cylinder, and in response to further slight movement of the main valve, to automatically render said pump functionally inoperative for propelling purposes.

A further object of my invention is to provide apparatus, as above set forth, which includes an improved valve mechanism for effecting the control of a hydraulic actuator system.

10 Still another object of my invention is to provide improved means whereby the timed movements of a plurality of hydraulic actuators may be effectively controlled and to this end I propose to provide improved mechanism which will

15 enable one actuator to experience a dwell of sufficient duration to permit the continued movement of another actuator and thereby enable the simultaneous return of both actuators upon the completion of their working strokes.

20 Another object of my invention is to provide apparatus, as above set forth, which includes an improved unitary pumping mechanism having a plurality of pumps, the delivery of which may be simultaneously controlled, and to carry out this

25 feature of the invention I provide a combined feed pump and charging pump structure so arranged as to enable the automatic variation in volumetric delivery of the charging pump in accordance with variations in displacement of the

30 feed pump. In this manner I propose to eliminate the necessity of operating a charging pump, such as a gear pump, continuously at its maximum charging rate as has been commonly done in the past, thereby eliminating by-passing of

35 fluid which necessarily causes deleterious increases in temperature of the fluid medium.

The foregoing and numerous other objects and advantages will be more apparent from the following detailed description when considered in connection with the accompanying drawings, wherein:

40 Figure 1 discloses a hydraulic system of control which is representative of one embodiment of my invention;

45 Figure 1A discloses the valve member in its rapid traverse approach position;

Figure 1B discloses the valve member in its rapid reverse position;

50 Figure 2 discloses a modified system of control wherein two low pressure or high displacement pumps are employed, one for charging the feed pump and the other for rapid traverse purposes, as distinguished from the system shown in Figure 1 wherein one low pressure or high displacement pump is employed;

Figure 3 is a sectional view of the main control valve mechanism similar to that disclosed in Figure 1, with the valve of the feed pump control device shown in its "central position," said view being a horizontal section taken substantially along the line 3—3 of Figure 4;

Figure 4 is a vertical sectional view of said valve mechanism taken substantially along the line 4—4 of Figure 3;

Figure 5 is a vertical sectional view of the valve mechanism taken substantially along the line 5—5 of Figure 4;

Figure 6 is a fragmentary horizontal sectional view of the valve mechanism taken substantially along the line 6—6 of Figure 5, said view being shown to more clearly disclose the passageway which serves to maintain communication between the opposite extremities of the valve chamber;

Figure 7 is a vertical transverse sectional view of the valve mechanism taken substantially along the line 7—7 of Figure 4;

Figure 8 is a transverse vertical section taken substantially along the line 8—8 of Figure 4;

Figure 9 is a transverse sectional view taken substantially along the line 9—9 of Figure 4;

Figure 10 is a transverse vertical sectional view taken substantially along the line 10—10 of Figure 4;

Figure 11 is a similar transverse sectional view taken along the line 11—11 of Figure 4;

Figure 12 is a similar transverse section taken along the line 12—12 of Figure 4;

Figure 13 is a transverse section taken along the line 13—13 of Figure 4;

Figure 14 is an enlarged detail view of the lower left-hand portion of the main control valve mechanism shown in Figure 4 to more clearly illustrate my improved means for effecting a dwell in an actuator piston prior to the shifting of the main control valve;

Figure 15 is a view similar to Figure 14 disclosing the unbalancing member shifted to its operative position;

Figure 16 is an enlarged central sectional view of one of the actuator cylinders and piston to more clearly illustrate the sealing device associated therewith;

Figure 17 is an enlarged central sectional view of the combined gear pump and plunger pump structure capable of being used in my improved system of control;

Figure 18 is a transverse sectional view of the plunger pump section taken substantially along the line 18—18 of Figure 17;

Figure 19 is an enlarged fragmentary view of the gear pump coupled with the plunger pump, said view being taken substantially along the line 19—19 of Figure 17;

Figure 20 is a vertical central view shown partly in elevation of a modified combined plunger pump and gear pump construction, said view differing from Figure 17 in that the plunger pump of Figure 20 is of the type equipped with a shiftable pintle for varying the pump displacement;

Figure 21 is an end elevational view of the pump of Figure 20 shown partly in section, said view being taken substantially along the line 21—21 of Figure 20;

Figure 22 is a circuit diagram similar to Figure 1 disclosing the shiftable control or valve members in positions illustrated in Figure 1A, directional arrows being employed to more clearly illustrate the direction of fluid flow in the various channels; and

Figure 23 is a view similar to Figure 22 disclosing the positions occupied by the slow traverse pump control element and the reversing valve when said slow traverse pump and fluid pressure generating means is operating to propel the actuators at a relatively slow speed, directional arrows being employed to more clearly illustrate the direction of fluid flow in the various conduits.

Referring now to the drawings more in detail wherein like numerals have been employed to designate similar parts throughout the various figures, it will be seen that one embodiment of my invention includes a system of hydraulic control of the type shown in Figure 1. Before taking up a description of the system shown in Figure 1, I wish to call attention to the fact that said system is made up of a number of important devices which I propose to designate generally by numerals so as to facilitate an understanding of the description which is to follow. My improved system includes a suitable reservoir 24, Figure 1, and a main control valve mechanism designated generally by the numeral 26. This control valve mechanism, in the disclosed embodiment, is made up of a main operating valve 28, a feed pump control mechanism 30, and a fluid balancing control device 32. A suitable rapid traverse pump 34, preferably of the gear pump type, is shown in operative association with the valve mechanism 26, and a feed pump or plunger pump 36 is also connected with said valve mechanism through the agency of the control mechanism 30. These pumps 34 and 36 are shown in detail in Figures 17 to 19 inclusive. A pair of hydraulic actuators 38 and 40 are hydraulically connected with the control valve mechanism in a manner later to be described. I have shown a rotary dog supporting plate or disk 42 mounted upon a shaft 44, and this shaft 44 is preferably rotated in timed relation with the movement of one of the actuators. For a more detailed description of this dog carrying disk, reference is made to my copending application, Serial No. 582,192, filed December 21, 1931, now issued as Patent No. 2,078,697, dated April 27, 1937.

It is believed that the structural and functional characteristics of the control valve mechanism 26, as well as the other elements of the system, will be more readily understood by describing said parts in connection with the method of operation. Consider that the pumps 34 and 36 are being driven from a suitable source of power supply, not shown, and that the main control valve 28 occupies the central position shown in Figure 1. It will be seen that this operating or control valve 28 is longitudinally shiftable within a casing 46 and is adapted to be manually shifted to the right by moving a control handle 48, Figure 5. Movement of the control handle 48 rotates a vertical shaft 50 which, in turn, is connected to the right end of the valve 28, Figures 1, 3, and 4, by means of an arm 52.

The position of the valve 28, as shown in Figures 1, 3, and 4, will hereinafter be referred to as its neutral or by-passing position, and it will be seen that when said valve occupies this position, fluid discharged from the feed pump 36 is directed through a conduit 54 and a conduit 56 to a port 58 which, at this instant, communicates with an annular passage 60 of a control member 62 which forms a part of mechanism previously referred to as the feed pump control mechanism 30. Fluid entering the passage 60 from the port 58 circulates through a port 64 and returns through a

conduit 86 to the intake side of the feed pump 36. Thus, the feed pump 36 is functionally inoperative with respect to either of the actuators 38 or 40 when the control member 62 and the main control valve 28 occupy the relative positions shown in Figure 1. Likewise, should the main control valve 28 be slightly shifted to the left of the position shown in Figure 1, the control member 62 would occupy the position shown in Figure 1, and thus the feed pump 36 would be functionally inoperative with respect to either of said actuators.

Fluid from the reservoir 24 is directed through a conduit 88 to the intake side of the rapid traverse pump 34 and is discharged from said pump through a conduit 70 to an intake port 72 in the valve casing 46. This fluid is directed through radial passages 74, Figures 1, 4, and 7, into a longitudinal passage 76 which communicates with an end chamber 78. This end chamber 78 communicates through a longitudinal passage 80, Figures 6 to 11 inclusive, with an oppositely disposed valve chamber 82, and this valve chamber 82 communicates with the reservoir 24 through a conduit 84 and a restricted orifice 86. Thus, when the valve parts occupy the relative positions shown in Figures 1, 3, and 4, fluid discharged by the rapid traverse pump 34 circulates through the valve and is returned to the reservoir, the restricted orifice 86 in this instance serving merely to maintain sufficient fluid pressure to retain the main valve 28 in balance. In other words, the back pressure set up by the restricted orifice 86 acts against the opposite ends of the valve communicating with the chambers 78 and 88 with equal force, and hence maintains the valve member 28 in balance. It will be understood of course that the valve is always in balance regardless of pressure acting thereon, due to the fact that the area at each end of the valve is the same, and further, that the fluid is adapted to unrestrictedly pass to both ends of said valve. The conduits for establishing communication between the chambers 78 and 88 for the purpose set forth above will be more clearly understood from the detailed description of the fluid balancing control device 32, as will later appear.

Assume now that the valve member 28 is shifted to the right from the position shown in Figure 1 to the position shown in Figure 1A and Figure 22. This movement is accomplished by manually shifting the control lever 48 so as to longitudinally move the valve member. This shifted position of the valve member may be referred to as a rapid approach position because at this time the system is conditioned for imparting rapid movement to the left of the piston 38^a of the actuator 38 and rapid movement to the left of the piston 40^a of the actuator 40. Tracing the fluid, we find that in this rapid approach position fluid from the rapid traverse pump 34 enters the valve port 72, passes through side passages 90 in the valve member 28 through a port 92 and then through conduit 84, distributor 96, and conduit 97, and then into the right end of the actuator 38 and through a conduit 98 into the right end of the actuator 40. Fluid from the left ends of the actuators 38 and 40 is returned through conduits 100 and 102 respectively to a valve port 104 which now communicates with the chamber 82 and consequently with the reservoir 24 through the restricted orifice 86. In this manner rapid movement to the left is experienced by each of the pistons 38^a and 40^a. The distributor mechanism 96 serves as a compensating means which may be

adjusted so as to permit the simultaneous actuation of both cylinders regardless of the fact that one may be subjected to a greater load than the other. Other devices, such as the well known rack and pinion mechanism having backlash to compensate for such variations, as shown in the American Machinist, dated August 4, 1927 (see particularly the statement in the first paragraph on page 207), may also be used without departing from the spirit and scope of my invention. As a further explanation of what I mean by the conventional rack and pinion mechanism, reference is also made to page 479 of the "American Machinist" for September 20, 1928, wherein another machine is disclosed which is equipped with a rack and pinion mechanism, and wherein this mechanism is described as being connected with each of the heads for the purpose of equalizing the movement of the heads.

It will also be apparent that upon shifting the valve member 28 to the right, a pressure is increased within the valve passages 90, due to the restriction of the radial passages 74 as they traverse their companion valve port 72, and this fluid pressure is transmitted to a chamber 106 of the feed pump control device through passages 108, 110, and 112. This causes the control member 62 to be suddenly shifted to the left, the fluid from the advancing side thereof passing outwardly through a passage 114, which then is in communication with the return chamber 82. This causes the control member 62 to be shifted to the position shown in Figure 1A, thereby preconditioning the circuit connected with the feed pump 36 for imparting a feeding movement to the pistons 38^a and 40^a upon the completion of the rapid approach movement of said pistons.

When the pistons 38^a and 40^a reach the limit of their rapid approach movement, a dog 116 on the disk 42 engages a finger 118 secured at the lower end of the stem or shaft 50 so as to automatically return the valve member 28 to a substantially central or neutral position as shown in Fig. 1 and in Fig. 23. As previously stated, the circuit, including the plunger pump 36, is now conditioned for directing fluid, under high pressure, into the right end of each actuator, due to the fact that the valve port 58 is now closed by the control member 62 (see particularly Fig. 23), thereby preventing free circulation of the fluid delivered to and discharged by the feed pump, as previously described. With the main valve 28 in its neutral or feeding control position the control member 62 is locked in position due to the sealing of valve passages extending between the main control valve and the control device 30. The fluid from the gear pump now circulates or by-passes through the restricted orifice 86, as previously described, and fluid from the advancing ends of the pistons 38^a and 40^a is directed through the valve passage 104 which now communicates with the annular passage 60 of the control member 62 through a passage 120, Figure 3. Thus, the plunger pump or feed pump 36 is connected in a closed circuit with the actuators for propelling same at a feeding rate, and the rapid traverse pump by-passes through the main valve.

Attention is directed to the fact that when the passage or port 74 shifts, a substantial difference in pressure is established between the chambers or passages 90 and 82. It is this difference in pressure that causes the valve member 28 to move with a "snap." Quick or sudden movement of the valve member 28 is very desirable. It should also be noted that the valve member 28 when

positioned as shown in Figure 1, prevents the valve member 62 from shifting. Fluid pressure at the forward end of the actuator cylinder temporarily becomes higher than the propelling pressure upon the completion of the piston stroke, but my improved construction precludes this sudden development of pressure from having any effect upon the valve member 62. That is to say, the valve member 62 is positively secured against shifting. It should also be noted that, when the valve is suddenly unbalanced for reversal only a slight travel of the valve will place the feeding circuit in neutral, and thereby allow a tool, such as a rotary cutter propelled by the hydraulic actuators to clean up its work on a piece of material without leaving any marks because several revolutions could be experienced before the rapid traverse fluid is put into play and the actuator returned.

We shall assume that it is desirable to arrest the movement of the actuator piston 40^a before the piston 38^a completes its feeding stroke. Thus, the piston 38^a continues after movement of the piston 40^a has been arrested and as it approaches the limit of its advancing movement, a dog 126 moves into engagement with the right end of a valve member 128 of the fluid balancing control device 32. A valve or plunger 122, the functioning of which is adjustably controlled by an abutment screw 124, is employed to automatically establish communication between opposite sides of the piston 40^a when it approaches the position shown in Figure 16. The shifting of the valve member 128 to the left, from the position shown in Figure 14 to the position shown in Figure 15, establishes communication between the valve chamber 88 and the reservoir 24 in a manner about to be described. When the valve member 128 occupies the position shown in Figure 14, communication between the valve chamber 88 and a conduit 130 unrestrictedly connected with the fluid reservoir 24 is broken, but when the valve member 128 is shifted to the position shown in Figure 15, fluid from the valve chamber 88 flows through a passage 132 into a valve chamber 134 which at this instant communicates with an adjustable needle valve 136 through a central valve passage 138, a radial port 140, and an annular passage 142. In this manner fluid flows from the valve chamber 88 at a speed determined by the setting of the valve 136 into a passage 144, Figure 15, an annular passage 146 of the valve member 128 and thence unrestrictedly back to the reservoir 24 through the conduit 130. The purpose of controlling the flow of fluid from the chamber 88 is to obtain a predetermined dwell or time control of the actuator pistons before reversal is imparted thereto, as will more clearly appear as the description progresses.

In order to more clearly understand the manner in which the valve chambers 78 and 88 are in communication when the main valve member 28 occupies its central or neutral position, reference is made to Figures 1, 12, 14, and 15. As previously described, the valve chamber 88 communicates with the chamber 134 of the control device 32 through the passage or conduit 132 (see Figures 14 and 15). With the valve member 128 in the position shown in Figure 14, the chamber 134 communicates with an annular chamber 135, and this chamber 135 communicates with the longitudinal valve passage 80 (Figure 12) through a passage 137. The extremity of the valve passage 80 oppositely disposed from the point of communication with the passage 137 communicates

with the valve chamber 78 (see Figure 6). Thus balanced fluid pressures exert equal force in opposed directions upon the valve member 28 so as to maintain the valve member in its central or slightly shifted position. That is to say, if the valve member 28 is shifted slightly to the left or to the right of the position shown in Figure 1, the balanced condition of the valve member 28 remains undisturbed. It will also be noted that the valve chamber 82 is maintained in constant communication with the longitudinal passage 80 as illustrated in Figures 6 and 10.

From the foregoing it will be apparent that when the valve member 128 is shifted to the left, it affects an unbalancing of the normal fluid pressure acting upon the main valve 28, thereby causing the fluid pressure within the right chamber 78 to move the valve 28 to the left at a speed determined by the setting of the needle valve 136. When the valve member 28 has shifted sufficiently to bring an annular valve port 148 into registration with the valve passage 144, the needle valve 136 is by-passed so as to permit the free or unrestricted flow of fluid from the chamber 88 through longitudinal passages 150 in the valve 28 which communicate with the annular port 148 as clearly shown in Figures 14 and 15. The radial passage 74 is enlarged slightly at the surface of the valve 28 by opposite recesses 74a. As the valve 28 moves to the left from the central position of Figures 1 and 23, communication is established between the port 72 and the port 104 before communication is cut off between the port 72 and the chamber 78 for the distance between the left side of the in-take port 72 and the right extremity of the right recess 74a of the radial port 74 is greater (as for example, in the order of .031 of an inch) than the distance between the right side of the port 104 and the right side of the enlarged valve section which controls this port. As the valve begins to uncover the port 104, fluid is admitted to the outer end of the actuator 38 and the movement of the actuator piston 38a to the right further assures maintenance of a sufficient pressure in the chamber 78 (the port 92 opening at the same time as the port 104) to cause the valve 28 to move to its extreme rapid reverse position as shown in Figure 1B. In this manner I am able to positively insure the sudden shifting of the valve 28 to its rapid reverse position shown in Figure 1B when the desired dwell in the actuator pistons has been experienced.

As the valve member 28 shifts to its left or rapid reverse position, fluid from the gear pump 34 within the valve passages 90 is directed through a passage 152 which communicates with passage 114 through a connecting passage 154, thereby causing the control member 62 to be suddenly shifted to the right. Fluid from the advancing end of the control member 62 is directed through the passage 112 into the end chamber 78 thereby permitting free axial movement of the control member to the right. With the control member 62 in this position, the plunger pump circulates through the annular passage 60, as previously described. When the pistons reach their starting position, a dog 156 engages a finger 158, Figures 1 and 5, thereby causing the valve 28 to be returned to its neutral position. It should also be noted that as the dog 126 moves away from the right end of the valve member 128, Figures 1, 14, and 15, a coil spring 160 automatically returns the valve member 128 to its normal position shown in Figure 14. A pin 162 serves to limit the movement of the valve member 128 to the right.

Attention is also directed to a vent or bleed passage 164 in the valve member 28 which serves, when said valve member 28 is in the position shown in Figures 1 and 3 and said control member 62 occupies the position shown in Figure 1A, to establish restricted communication between the closed fluid circuit containing the plunger pump 36 and the low pressure fluid supply. In other words, when the circuit is in feeding condition as shown in Figure 23, if there is any difference in volumetric displacement between opposite sides of the actuator pistons, this will be compensated for by the presence of the bleed passage or vent 164, and further, if there should be any slight leakage of fluid due to the wear in the piston rods, failure of the actuator packings, etc., said vent would serve to compensate for such leakage. In no sense should the presence of this vent 164 be confused with devices heretofore employed to "make up" fluid losses due to slippage of fluid through pump valves, etc., which is commonly experienced in conventional fluid circuits. In fact, the size of the vent 164 is so small that it will have no effect whatsoever on pressure conditions within the closed circuit, except for such on the inlet side of the plunger pump as merely serve to compensate for slight volumetric variations, as above set forth. Attention is also directed to a similar vent or passage 166, Figures 1 and 3, which functions similarly to the vent 164 when the control member 62 occupies the position shown in Figures 1 and 3.

As has been previously set forth, the radial ports 74 in the valve 28 are provided at each side thereof with oppositely disposed recessed portions 74a. These portions 74a serve to provide restricted communication between the discharge side of the low pressure pump 36 and the outlet passage 16 as said valve is shifted to either side of its neutral position. In other words, as said valve shifts to one side, the restricted communication referred to above, causes an increase in pressure within the valve passages 90 which is transmitted to the control member 62 before the valve passages 90 actually register with the companion valve passages or ports 92 and 164. As previously described, the passages 152 and 168 serve to establish communication between the valve passages 90 and the control member 62 before the valve 28 actually cuts in the low pressure fluid for propelling purposes. The importance of this structural arrangement will be apparent when it is understood that I am able to control the functioning of the closed circuit which includes the feed pump 36 without affecting or changing the functioning of the low pressure circuit which includes the gear pump 34. In other words, by merely shifting the main valve 28 to the right a sufficient distance to establish communication between the valve passages 90 and the passage 168, Figure 1, I am able to cause the control member 62 to shift to the left without actually cutting in the low pressure fluid. Likewise, if the valve member 28 is shifted slightly to the left from its neutral position so as to register the valve passages 90 with the passage 152, the control member 62 will automatically shift to the right so as to render the closed circuit, including the feed pump 36, functionally inoperative for propelling purposes without cutting in the low pressure fluid. By this arrangement I am able to eliminate conventional clutch mechanism, etc., heretofore employed in many instances to control the operative functioning of fluid pumps and the like. Furthermore, my improved system of con-

trol enables the starting and stopping of an actuator to be controlled independently of the rapid traverse propelling mechanism, such as the rapid traverse gear pump shown therein.

Attention is also directed to the sealing arrangement which I employ to prevent the leakage of fluid longitudinally of the actuator pistons 38a and 40a (see Figure 16). It will be seen that these pistons are provided with a pair of annular recesses 167 adapted to retain a plastic or impressionable sealing medium 169 which may be delivered, under pressure, into the left end of the piston rod 171 through a longitudinal recess 173 which communicates with a chamber 175 within the piston. By means of a spring pressed plunger 177 the plastic sealing medium 169 is continuously maintained under pressure. This sealing medium is preferably a compound including suitable grease, graphite and binding material. Thus, the sealing material within the annular grooves 167 serves to positively prevent the slippage or leakage of fluid from the high to the low pressure sides of the piston. It should also be noted that, while the grooves 167 serve to retain grease in position, grease may also fill up the space between the two piston rings, or, in other words, provide an effective grease film, which operates with the annular grease sections in the grooves 167 in preventing slippage of fluid from one side of the piston to the other.

Attention is also directed to the manner in which I seal the fluid within the valve chamber 18, Figure 5, against leakage along the shaft or stem 58. I provide said stem with a pair of annular grooves 58a and connect these grooves through passages 179 with the reservoir 24. Thus, any fluid, under pressure from the valve chamber 18 which may reach the annular grooves or recesses 58a, will be directed back to the reservoir 24 and hence will not leak to the outer ends of the stem 58. It will be seen that a passage 181, Figures 5 and 7 to 10 inclusive, is provided in the valve casing 48 and this passage 181 communicates with the passage 144 and thus serves to establish communication between the passages 179 and the fluid reservoir.

In Figure 2 I have disclosed a modified circuit arrangement which is designed to employ a feed pump which requires a charging pump to constantly deliver fluid thereto. In this circuit of Figure 2 I employ the same valve mechanism designated generally by the numeral 28 and the same fluid reservoir 24 as well as a similar rapid traverse pump 36. A feed pump 36a is shown which is continuously coupled with the discharge side of a charging pump 34 which may be similar in structural characteristics to the gear pump 34. The only difference in structural arrangement of the circuit shown in Figure 2 is that instead of connecting the plunger pump 36a in a closed circuit which is functionally independent of any low pressure fluid, I employ the additional charging pump 34a which continuously charges the pump 36a. The pump 36a might be one of the conventional pumps now employed wherein considerable slippage of fluid is experienced, thereby requiring a charging pump, such as the pump 34a, to be continuously connected therewith to "make up" fluid lost as the result of said slippage.

Referring now to Figures 17 to 19 inclusive, it will be seen that one form of pumping mechanism which is capable of use in my improved system of control includes a combined plunger and gear pump device indicated generally by the

numerical 168. This pumping mechanism or unit 168 is made up of the feed or plunger pump 36 and the gear pump 34. The gear pump 34 is made up of a pair of gears 170 and 172 which are enclosed within casing sections 174 and 176. Side plates 178 and a central casing section 180 co-operate with the casing sections 174 and 176 to provide a suitable housing for the gears 170 and 172 as clearly shown in Figure 17. Power is transmitted to the gear 170 from any suitable source of supply (not shown) through a drive shaft 182 which is connected by a pin 184 to a sleeve 186 with which the gear 170 rotates as a unit. A central adjustable valve member 188 which is provided with peripheral ports 190 is adapted to receive and convey fluid from radial passages 192 within the gear 170 which is directed through said passages when the teeth of said gear mesh with the teeth of the companion gear 172. Valve 188 may be adjusted by rotating a graduated disk 194, Figure 17, which operates through a pinion 196 and a quadrant 198 meshing therewith, said quadrant being secured to the outer end of a stub shaft 200 which makes a tongue and groove connection with the valve 188, as clearly shown in Figure 17. When the valve 188 occupies the position shown in Figures 17 and 19 and the gears rotate in a direction indicated by the arrows, a portion of the fluid received by the discharge chamber 202 of the pump is adapted to pass through the radial passages 192 to the intake chamber 204. In order to increase the fluid delivery from the discharge chamber 202, it is only necessary to adjust the valve 188 in a counterclockwise direction, as viewed in Figure 19, thereby reducing the amount of fluid which is by-passed from the high to the low pressure chambers. In fact, the valve can be so adjusted that no fluid is by-passed from the chamber 202 to the chamber 204 and in this position the pump is operating at its maximum delivery. When the pumping unit 168 is employed in the system shown in Figure 1, fluid passes into the gear pump chamber 204 from the conduit 68 and is delivered from the discharge chamber 202 through the conduit 70 which connects with the main control valve mechanism.

The plunger pump 36 includes a plurality of radially reciprocable pistons or plungers 206 which are successively urged outwardly to deliver fluid at high pressure from the chambers at the outer ends of said pistons through the agency of an adjustable eccentric driving ring 208. A tapered valve 210 is employed to control the flow of fluid toward and away from the outer ends of the pump pistons 206. Fluid received by the plunger pump from the conduit 68 enters the chamber 212 and is successively directed by a peripheral port 214 to the pistons which are experiencing an intake stroke. A valve port 216 receives fluid under high pressure and directs the same to the discharge conduit 54.

The eccentricity of the driving ring 208 is occasioned in response to manual manipulation of the graduated adjusting disk 194. Turning of this disk causes a member 218 to shift longitudinally within a driving sleeve 220, and the inner end of this member 218, through the agency of an inclined projection 222, is coupled with a laterally adjustable driving member 224 which, at its right end, Figure 17, supports the driving ring 208 with anti-friction bearings. Thus, by urging the member 218 to the left, within the driving sleeve 220, the driving member 224 is shifted laterally or upwardly, as seen in Figure 17, thereby

varying the eccentricity of the driving ring 208. For a more detailed disclosure of the tapered valve arrangement disclosed in Figure 17, reference is made to Figure 25 of my Patent 2,078,697, the application for which was filed December 21, 1931, and Figure 4 of my Patent 2,036,162, the application for which was filed September 13, 1930.

From the foregoing it will be apparent that by a single adjustment of the graduated disk 194, the delivery of the gear pump, as well as the displacement of the plunger pump, will be simultaneously varied. This arrangement is such that in instances where the gear pump might be employed to charge the plunger pump, an increase in displacement of the plunger pump occasioned by movement of the member 194 would automatically effect an increase in volumetric delivery of the gear pump to the plunger pump. In many systems of control of the conventional type, wherein gear pumps are employed to charge plunger pumps, the gear pumps are continuously operated at maximum charging rate which is usually in excess of that required by the plunger pumps, and in order to take care of excess fluid not required for charging purposes, relief valves must be employed. I propose to provide a pumping mechanism wherein the volumetric discharge of fluid of the gear pump may be controlled in accordance with the needs or requirements of the plunger pump. In this way increases in fluid temperatures resulting from by-passing fluid when relief valves and the like are employed, is eliminated.

In Figure 1 I have shown a system wherein the plunger pump need not be charged by the gear pump during its functioning in the closed circuit, whereas in Figure 2 I have shown a circuit arrangement wherein the gear pump or charging pump is continuously connected with the plunger pump. Thus, in Figure 2 a plunger pump and charging pump unit simulating that shown in Figures 17 to 19 inclusive may be employed. In describing the system shown in Figure 2 I stated that the gear pump 34* will serve to take care of fluid leakage within the pump 36* and wish to call attention to the fact that when a pumping unit, such as that disclosed in Figures 17 to 19 inclusive is employed, the problem of fluid leakage within the plunger pump is eliminated by the presence of the tapered valve 210. A film of oil is maintained along the peripheral surface of the tapered valve 210. This film serves as a fluid seal. Due to the tapered peripheral surface, there is a tendency during the rotation of the valve for the film to slowly migrate toward the larger extremity of the valve. However, this slow migration of fluid must be clearly distinguished from the deleterious effects which have heretofore been experienced in connection with the use of pumps equipped with cylindrical valves or pintles. In these latter devices the leakage of fluid along the peripheral surface of the cylindrical valve member not only results in the loss of fluid, but also in the development of high temperatures. Even though the fluid film along my tapered valve may slowly migrate toward the larger end thereof, this fluid eventually reaches the grooves shown toward the left end of the valve, and from this point is conducted back to the system.

The above mentioned migration of the fluid must be clearly distinguished from what is commonly referred to in the field of hydraulic con-

control for machine tools and the like as fluid slippage. That is to say, fluid slippage usually implies a certain amount of power loss due to the slippage of fluid through a restricted area or orifice. If the word "slip" were employed to describe the slow migration of fluid along my valve, such a use of the term should not imply "fluid slippage" as I have referred to above. In fact, by employing the tapered valve construction disclosed herein I am able to connect the pump in a closed circuit with the actuator and thereby cause fluid on opposite sides of the actuator to be moved as a confined body or unit. That is to say, there is an absence of slippage inasmuch as the two fluid bodies or units are maintained intact.

In Figures 20 and 21 I have shown a pumping unit designated generally by the numeral 168^a which is of the type wherein the plunger pump is of such a construction as to require the continuous delivery thereto of charging fluid in order to take care of fluid slippage. This unit 168^a is the type of unit specifically referred to in connection with Figure 2. This unit 168^a includes a plunger pump 36^a which is similar in structural and functional characteristics to the plunger pump shown in the Ferris Patent No. 1,753,562, and employs a rotary driver 226 for imparting reciprocation to a plurality of radial pistons or plungers 228. A cylinder barrel 230 is carried by a laterally adjustable pintle 232 equipped with valve ports 234 and 236 which are adapted to control the flow of fluid toward and away from the pistons 228. Fluid from the plunger pump is taken in by a conduit 238 and is discharged, under high pressure, through a conduit 240. This conduit 238 connects with the discharge chamber 242 of the gear pump indicated generally by the numeral 34^a. This gear pump is similar in structural and functional characteristics to the gear pump 34 previously described in connection with Figures 17 to 19 inclusive and includes a pair of gears 170^a and 172^a. The gear 170^a is driven by a shaft 244 which also serves as the drive shaft for the plunger pump driver 228. Fluid is directed to the intake chamber 248 of the gear pump 34^a, Figure 21, from a conduit or pipe line 248 which connects with a reservoir 250, Figure 20. A valve 188^a similar to the valve 188 of the gear pump 34, is adapted to be adjusted by manual manipulation of a handle 252 keyed to a shaft or stem 254. This shaft carries a pinion 256 which meshes with a quadrant 258 connected with the valve 188^a and said shaft 254 also serves, at its right extremity, to adjustably control the displacement of the plunger pump 36^a. Thus, when the handle 252 is shifted to increase the displacement of the plunger pump 36^a, the valve 188^a of the gear pump simultaneously shifts so as to increase volumetric delivery thereof. In this manner, as described in connection with the pump unit 168, the volumetric discharge of the gear pump is controlled in accordance with the needs of the plunger pump. The main difference in functional characteristics between the pump units 168 and 168^a resides in the fact that the plunger pump 36^a of the unit 168^a is of the type which normally experiences considerable fluid slippage along the cylindrical pintle or valve 232 and therefore the gear pump must be set at a rate of fluid delivery which will take care of this leakage. The pump unit 168, on the other hand, is of such a construction that the gear pump need only be set for the amount of fluid which is actually discharged by the plunger pump, taking into

consideration, of course, any slight leakage which might be experienced due to normal wear in the parts or deterioration of the valve packings. The units 168 and 168^a each employ the principle of the simultaneous control of the feed pump displacement and the charging pump delivery. It will, of course, be understood that when a system, such as that disclosed in Figure 1, is employed, the plunger pump and gear pump may be operated independently as distinguished from the interlocked pump arrangement shown in Figures 17 to 21 inclusive.

I have endeavored in the foregoing description and in the drawings to set forth the novel features of control embodied in the present invention, which distinguish from other hydraulic propelling devices and controls in use prior to this invention. However, the functional characteristics of hydraulic circuits, when in actual operation, are difficult to visualize, even though the description of the various parts is fully set forth. In considering the functional characteristics of the invention, as hereinbefore described, attention is directed to the fact that the hydraulic actuator, such as the actuator structure 38, must not only shift to propel a machine part, but even more important, the fluid must be delivered to the actuator in such a manner as to maintain a definite speed relation between the actuator and the volumetric delivery of fluid thereto. In conventional mechanical structures "backlash" is present, which may be caused by required clearance and wear of the parts. The present invention enables complete elimination of "backlash" because the volumetric delivery of fluid to the actuator is controlled and maintained exactly in accordance with the required speed of travel of the actuator irrespective of load conditions.

During rapid traverse movement, fluid is drawn from the reservoir 24 and delivered through either conduit 94 or conduit 100 to the actuator 38. The valve member 28 also serves to return the fluid flow from the actuator 38 to the reservoir through the pipe line 84. The orifice 86 causes a restricted flow of fluid and thereby maintains the system under pressure. When the valve member 28 is shifted to the left or to the right, fluid is dispatched to the actuator 38 and presents openings of equal size in both the forward and the return ends, thereby presenting a control both to and from the actuator. This feature is particularly important when considered in connection with the cutting-off of the rapid traverse pump, because under such circumstances a positive control of the fluid flow both to and from the actuator positively and accurately synchronizes the speed of valve and actuator movement. It will be noted that when the feed pump 36 is functionally operative, it is coupled in series with the actuator 38. There are no relief valves functionally operable during this feeding movement, and the vent 184 does not change the closed circuit functioning during said feeding action. As previously set forth herein, this vent is so small that it does not preclude movement of fluid as a unit from the discharge side of the pump to the intake side of the actuator and from the discharge side of the actuator to the intake side of the pump. In other words, a truly closed circuit arrangement is maintained during the feeding action.

The above described valve means also serves to instantaneously effect the change in speed of the actuator. In other words, there is no time ele-

ment between the change from one speed to another, as is common among conventional hydraulic systems of control. The fact that the ports or fluid conducting passages, extending between the chamber of the valve member 28 and the chamber of the control member 62, are so short precludes any time lag in shifting from one speed to another, for example, in shifting from rapid traverse to feed. In fact this positive and accurate control, accomplished when the valves are shifted from one position to another, constitutes a distinct advancement over conventional systems with which I am familiar.

Attention is directed to the fact that the control device 32 includes a speed or time control mechanism, namely, the needle valve 136 and also a control determinative or member 128, said control determinative being adapted to be engaged by the dogs or control abutments on the rotary control member 42. Thus the time or speed control valve 136 allows fluid to be slowly removed from the chamber 88 in accordance with the setting of the valve. Fluid channels 152-154 (Figure 3), when the valve member 28 has been moved a sufficient distance to the left, permit the control member 62 to be shifted to the right under fluid pressure, thereby rendering the feed pump 36 functionally inoperative. Following this a predetermined dwell takes place which is of sufficient duration—for example, to permit a clean-up cut to be taken by a cutting tool in instances where the hydraulic circuit and control disclosed herein are embodied in a machine tool.

When the valve member 28 has shifted so as to move the port 150 into communication with the conduit 144, sudden shifting of the valve 28 to its reverse position takes place, and the actuator is caused to move in a reverse direction at a rapid rate. The pressure, namely, the pressure developed by the feed pump 36, is relieved before the fluid motor or actuator is reversed. This is of the utmost importance in connection with the proper functioning of the hydraulic system. In conventional devices prior to the present invention where a dwell is required, the pressure has not been relieved in the manner disclosed herein. It will be apparent, therefore, that the control mechanism disclosed herein provides a very practical and satisfactorily operable arrangement for hydraulic actuator systems.

Obviously the invention is not limited to the specific disclosures herein, but is capable of other modifications and changes without departing from the spirit and scope of the appended claims.

Having thus described my invention, what I claim as new and desire to secure by Letters Patent is:

1. In a hydraulic actuator system, an actuator for propelling machine parts and the like, slow traverse pump mechanism for delivering fluid to said actuator at a relatively slow rate to propel said actuator at a relatively slow rate, rapid traverse pump means for propelling said actuator at a faster rate, shiftable valve means within a housing, a fluid circuit including said rapid traverse pump means, said valve means and said actuator, said valve means in one position serving to render said rapid traverse pump means effective to actuate said actuator and in another position to render said rapid traverse pump means ineffective to actuate said actuator, two-position shiftable control means in one position rendering said slow traverse pump mechanism effective to actuate said actuator and in the other position

5 ineffective to actuate said actuator, and means for shifting said control means as an incident to the shifting of said valve means a distance insufficient to render said rapid traverse pump means effective to actuate said actuator.

2. In a hydraulic actuator system, an actuator for propelling machine parts and the like, slow traverse pump mechanism for delivering fluid to said actuator at a relatively slow rate, rapid traverse pump mechanism for delivering fluid to said actuator at a faster rate, a shiftable operating valve for controlling the flow of fluid from said rapid traverse pump mechanism to said actuator, fluid pressure actuated control means operable in one position to render said slow traverse pump mechanism effective to propel said actuator and in a second position to short circuit said slow traverse pump mechanism to render it ineffective to propel said actuator, and means for supplying fluid to said control means under the control of said valve to shift said control means to said short circuit position when said operating valve connects said rapid traverse pump mechanism with said actuator for propelling purposes.

25 3. A hydraulic actuator system including an actuator, a power driven relatively slow delivery pump for delivering fluid to said actuator at a uniform slow rate, means connecting said slow delivery pump in a closed circuit with said actuator for rendering said slow delivery pump effective to actuate said actuator at the slow rate, a power driven rapid traverse pump for delivering fluid to said actuator at a relatively rapid rate, a reversing valve having a shiftable control member, said 30 valve having passages for directing fluid from said rapid traverse pump selectively to either side of said actuator under the control of said member and passages through which fluid flows during shifting of said valve member in one direction, and control means including means operable by fluid flowing through the last mentioned passages of the reversing valve during the shifting of said reversing valve control member in said one direction to render said slow delivery pump ineffective to actuate said actuator.

4. A hydraulic actuator system including an actuator, a slow traverse pump for delivering fluid at a relatively slow rate to said actuator, a rapid traverse pump for delivering fluid at a faster rate to said actuator, shiftable valve means for selectively controlling the fluid connection of at least one of said pumps with said actuator for propelling purposes, means associated with said valve means and operable in a given shifted position thereof to restrict fluid flow from one of said pumps whereby to increase fluid pressure within said valve means for control purposes, and shiftable control means operable as an incident to the aforesaid increase in pressure within said valve means for controlling the actuation of the actuator by the other of said pumps.

5. In a hydraulic actuator system, a reciprocable actuator, a pump for delivering propelling fluid to said actuator, a valve member shiftable to a plurality of positions for controlling the direction of fluid flow to said actuator from said pump, said valve member being normally balanced by fluid pressure, and mechanism shiftable in response to the movement of said actuator in one direction for causing momentary unbalancing of fluid pressure acting upon said valve member for shifting purposes and including means for causing a predetermined dwell of said actuator before the actuator moves in a reverse direction.

70 6. In a hydraulic actuator system, a reciproc-

cable actuator, a pump for delivering propelling fluid to said actuator, a valve member shiftable to a plurality of positions for controlling the direction of fluid flow to said actuator from said pump, said valve member being normally balanced by fluid pressure, and mechanism shiftable in response to the movement of said actuator in one direction for causing momentary unbalancing of fluid pressure acting upon said valve member for shifting purposes and including means for causing an initial retardation in the shifting of said valve and a subsequent sudden shifting thereof, whereby to enable said actuator to experience a predetermined dwell and the valve member to experience complete shifting before the actuator moves in a reverse direction.

7. In a hydraulic actuator system, a reciprocal actuator, a pump for delivering propelling fluid to said actuator, a valve member shiftable to a plurality of positions for controlling the direction of fluid flow to said actuator from said pump, said valve member being normally balanced by fluid pressure, and mechanism shiftable in response to the movement of said actuator in one direction for causing momentary unbalancing of fluid pressure acting upon said valve member for shifting purposes and including an adjustable bleed passage connected with said valve for controlling the rate of flow of balancing fluid from the vicinity of said valve member and thereby govern the period of dwell of the actuator before said actuator moves in a reverse direction.

8. In a hydraulic actuator system, an actuator, a variable displacement feed pump connected to said actuator to supply fluid to said actuator at rates determined by the rate of displacement of fluid by said pump, a variable delivery pump connected to said feed pump to supply charging fluid to said feed pump, and mechanical coupling means for simultaneously and proportionally varying the delivery of both said pumps.

9. In a hydraulic actuator system, an actuator, a variable displacement feed pump for delivering fluid to said actuator at a relatively slow rate, a variable delivery charging pump hydraulically connectable with said feed pump, and mechanical coupling means for simultaneously varying the delivery of both pumps, whereby the charging pump will vary its volumetric delivery in accordance with the rate at which fluid is displaced by the feed pump.

10. In a hydraulic actuator system for moving machine parts and the like, a fluid motor, a first pump for supplying fluid at a rapid rate to said motor, a second pump for supplying fluid at a slower rate to said motor, a fluid circuit including a control valve connecting one of said pumps to said motor to impart movement to said motor, said valve including a shiftable member and means cooperating with said member to restrict fluid flow in said circuit during movement of the member whereby to establish a momentary increase in pressure in said circuit, and fluid actuated means operably connected to said circuit for operation at said increased pressure to control the flow of fluid from said other pump to said actuator.

11. In a hydraulic actuator system for propelling machine parts and the like, a hydraulic actuator, a rapid traverse fluid circuit including pumping means for delivering fluid at a relatively rapid rate to said actuator, a relatively slow traverse fluid circuit including pumping means for delivering fluid at a relatively slow rate to said actuator, and valve mechanism including a

shiftable piston type valve member for controlling the direction of fluid delivery from said rapid traverse pumping means to said actuator and for causing pressure variations in fluid flowing through said valve mechanism, said valve mechanism also including a shiftable piston type valve member shiftable independently of said first mentioned valve member rendering said slow traverse pumping means selectively effective or ineffective to supply fluid to said actuator through said slow traverse fluid circuit, said independently shiftable valve member being operable in response to the aforesaid pressure variations in the fluid flowing through said valve mechanism.

12. A system of hydraulic control including a hydraulic actuator, slow traverse pumping means for delivering fluid at a relatively slow rate to said actuator to actuate said actuator at a relatively slow rate, rapid traverse pumping means for delivering fluid at a relatively rapid rate to said actuator to actuate said actuator at a relatively rapid rate, and control valve mechanism including a shiftable valve member for controlling the direction of fluid delivered to said actuator from said rapid traverse pumping means and another shiftable valve member for selectively rendering the slow traverse pumping means effective or ineffective to actuate said actuator, one of said valve members having means for developing variations in pressure of fluid flowing through said valve mechanism and the other of said valve members being shiftable in response to said pressure variations.

13. In a hydraulic actuator system, a reciprocal hydraulic actuator, fluid pressure generating means for delivering fluid under pressure to said actuator at one rate, a fluid circuit including said fluid pressure generating means and a reversing valve means for controlling the direction of fluid delivery to said actuator from said fluid pressure generating means, a second fluid pressure generating means for delivering fluid under pressure at a different rate to said actuator, two-position control means in one position rendering said second fluid pressure generating means ineffective to actuate said actuator and operable in response to the shifting of said reversing valve means to render said second fluid pressure generating means effective to actuate said actuator, said control means comprising a cylinder and piston, said reversing valve means including a shiftable valve member, passages controlled by said member for connecting said cylinder on opposite sides of said piston to the fluid circuit of the first fluid pressure generating means, and means cooperating with said shiftable valve member to establish a momentary increase in the pressure of fluid transmitted through said passages to one side of said piston to shift said control means as the reversing valve member is shifted in one direction and prevent shifting of said control means as the reversing valve member is shifted in the opposite direction.

14. In a hydraulic actuator system, a reciprocal actuator, fluid pressure generating means for directing fluid under pressure to said actuator at a given rate, shiftable reversing valve means for controlling the direction of fluid flow to said actuator from said fluid pressure generating means, a second fluid pressure generating means for delivering fluid to said actuator at a different rate, two-position shiftable control means in one position rendering said second fluid pressure generating means ineffective to actuate said actuator and operable in response to the shifting of said

valve means to render the second fluid pressure generating means effective to actuate said actuator, said valve means having a fluid replenishing vent hydraulically in communication with said first and second fluid pressure generating means, and channel means hydraulically coupling said first fluid pressure generating means and said reversing valve means for supplying fluid to the reversing valve means to maintain said reversing valve means hydraulically in balance.

15. In a hydraulic actuator system, a reciprocable actuator, a first pump for supplying fluid under pressure to said actuator at a given rate, a fluid circuit including a reversing valve connecting said pump to said actuator, said valve comprising a housing and a shiftable valve member in said housing, said housing having fluid ports controlled by said valve member to control the direction of fluid flow to said actuator, a second pump for supplying fluid to said actuator at a different rate, hydraulically shiftable control means for selectively rendering said second pump effective or ineffective to supply fluid to said actuator, fluid conducting means hydraulically coupling said control means with said reversing valve for operating said control means in response to movement of said shiftable reversing valve member in a given direction to render said second pump effective to supply fluid to said actuator, and means including a fluid replenishing vent in said reversing valve establishing communication between the first pump and the second pump when said second pump is rendered effective to supply fluid to the actuator.

16. In a hydraulic actuator system, an actuator, a first fluid pressure generating means for supplying fluid to said actuator at a given rate, a fluid circuit including said pressure generating means and said actuator, a control valve in said circuit, said control valve controlling the connection of said pressure generating means to said actuator, said valve comprising a housing and a shiftable valve plunger, said housing having an outlet port through which the fluid in said circuit flows and a chamber from which substantially unrestricted communication is established to said port when said plunger is in one position, said plunger being constructed to restrict communication between said port and chamber when the valve plunger is shifted to a second position to increase the pressure of fluid in said chamber, a second fluid pressure generating means for supplying fluid to said actuator at a different rate, two-position fluid actuated means in one position rendering said second fluid pressure generating means ineffective to supply fluid to said actuator and in the other position rendering said second fluid pressure generating means effective to supply fluid to said actuator, and means for supplying fluid from said chamber of the control valve housing to said fluid actuated means to move said means from one of its said positions to the other of its said positions when said valve plunger is moved to its said second position.

17. In a hydraulic actuator system comprising a fluid motor for imparting movement to a member at different speeds, a first circuit for supplying fluid to said motor at a high rate to impart a high speed to the member, a second circuit for supplying fluid to said motor at a lower rate to impart a lower speed to the member, and valve means governing the rate at which fluid is supplied to said motor to determine the speed of movement of the member, said valve means being operable to render one of said circuits effective or

ineffective, selectively, to supply fluid to the motor, and said valve means including means for varying the pressure of the fluid in said one circuit and means responsive to said variation in pressure for rendering said other circuit effective or ineffective, selectively, to supply fluid to said motor.

18. A hydraulic actuator system comprising a hydraulic motor, a first means for supplying fluid to said motor at a high rate to impart a rapid traverse movement to the motor, a second means for supplying fluid to said motor at a lower rate to impart a slow traverse movement to the motor, a first control means having one position of adjustment rendering said first fluid supplying means ineffective to supply fluid to the motor, and a second position of adjustment rendering said first fluid supplying means effective to supply fluid to said motor, a second control means having one position of adjustment rendering said second fluid supplying means ineffective to supply fluid to the motor, and a second position of adjustment rendering said second fluid supplying means effective to supply fluid to the motor and means cooperating with said first control means and said second control means for operating said second control means when said first control means is shifted partially from one of its said positions of adjustment toward the other of its said positions of adjustment to move the second control means from one of its positions of adjustment to its other position of adjustment.

19. In a hydraulic actuator system comprising a hydraulic motor, a first means for supplying fluid to said motor at a relatively slow rate to impart a slow traverse movement to the motor, a second means for supplying fluid to said motor at a higher rate to impart a rapid traverse movement to the motor, a first control means having one position of adjustment rendering said first fluid supplying means effective to supply fluid to the motor and a second position of adjustment rendering said first fluid supplying means ineffective to supply fluid to the motor, a second control means having three positions of adjustment, in one of which it renders said second fluid supplying means effective to supply fluid to the motor, and in the second of which it renders the second control means ineffective to supply fluid to the motor, and means cooperating with said second control means when in its third position of adjustment to move the first control means from one of its positions of adjustment to its other position of adjustment.

20. A hydraulic system comprising a hydraulic motor, a first means for supplying fluid to said motor at a high rate to impart a rapid traverse movement to the motor, a second means for supplying fluid to said motor at a lower rate to impart a slow traverse movement to the motor, fluid actuated means movable to two positions, in one of which it renders said second means effective to supply fluid to the motor, and in the other of which it renders said second means ineffective to supply fluid to the motor, and a control valve governing the supply of fluid to said motor by said first means and having a first position of adjustment rendering said first means effective to supply fluid to the motor, a second position of adjustment rendering said first means ineffective to supply fluid to the motor, and other selective positions of adjustment directing fluid to said fluid actuated means to operate said fluid actuated means to one or the other of its said two positions.

selectively, while rendering said first means ineffective to supply fluid to the motor.

21. In a hydraulic system, a first fluid circuit including a fluid motor and a first source of fluid under pressure, a second fluid circuit including said fluid motor and a second source of fluid under pressure, a two-position control valve in said first circuit for rendering the first circuit effective or ineffective, selectively, to supply fluid to said motor, said valve comprising a housing and a shiftable valve plunger, said housing having an outlet port and a chamber from which substantially unrestricted communication is established to said port when said plunger is in one position, said chamber being in communication with said first source, said plunger being constructed to restrict communication between said port and chamber when the plunger is shifted to a second position to increase the pressure of fluid in said chamber, fluid actuated control means responsive to a differential in pressure between said chamber and port to control the flow of fluid in the second circuit from said second source to said motor, and means for supplying fluid from the first source to said control means at the pressure of the fluid in said chamber, and exhausting fluid from said control means at the pressure of the fluid in said port.

22. In a hydraulic actuator system, a fluid motor, fluid pressure generating means for supplying fluid to said motor to actuate said motor, a fluid circuit including a control valve connecting said fluid pressure generating means to said motor, said control valve including a housing and a valve member shiftable therein from a first position to a second position to control the flow of fluid from said pressure generating means to said motor, said housing having a pair of chambers therein for receiving fluid, said shiftable valve member having opposing surfaces, one of which is subject to the pressure of the fluid in one chamber and the

other of which is subject to the pressure of the fluid in the other chamber, means for supplying fluid from said pressure generating means to both of said chambers at equal pressure when the shiftable valve member is in one position for maintaining the valve member hydraulically in balance, means for shifting said valve member from the first position to the second position, said means including instrumentalities for rendering the means for supplying fluid to the chambers ineffective to supply fluid to one of said chambers while continuing the supply of fluid to the other of said chambers, and means for discharging the fluid from said one chamber at a predetermined rate to permit and time the movement of said valve member to the second position under the action of the fluid supplied to the other chamber.

23. In a hydraulic actuator system, a fluid motor, a first pump for supplying fluid at a rapid rate to said motor, a second pump for supplying fluid at a slower rate to said motor, fluid actuated control means reversely operable to render said second pump effective or ineffective, selectively, to supply fluid to the motor, a rapid traverse fluid circuit including a control valve through which the fluid flows toward the motor at the rapid rate from the first pump, said control valve having a first adjustment rendering said first pump effective to supply fluid to the motor to drive the motor in one direction, and a second adjustment rendering said first pump effective to supply fluid to the motor to drive the motor in an opposite direction, and means to supply fluid from said rapid traverse circuit under the control of said valve to said fluid actuated control means to impart movement thereto in one direction or in an opposite direction, selectively, upon selective adjustment of the rapid traverse control valve from the first position of adjustment toward the second position of adjustment, and reversely.

40 ERNEST J. SVENSON.

CERTIFICATE OF CORRECTION.

Patent No. 2,363,707.

November 28, 1944.

ERNEST J. SVENSON.

It is hereby certified that error appears in the printed specification of the above numbered patent requiring correction as follows: Page 5, second column, line 29, for "groves" read --grooves--; page 9, second column, line 8, claim 11, after "member" insert --for--; and that the said Letters Patent should be read with this correction therein that the same may conform to the record of the case in the Patent Office.

Signed and sealed this 29th day of May, A. D. 1945.

Leslie Frazer

(Seal) Acting Commissioner of Patents.

selectively, while rendering said first means ineffective to supply fluid to the motor.

21. In a hydraulic system, a first fluid circuit including a fluid motor and a first source of fluid under pressure, a second fluid circuit including said fluid motor and a second source of fluid under pressure, a two-position control valve in said first circuit for rendering the first circuit effective or ineffective, selectively, to supply fluid to said motor, said valve comprising a housing and a shiftable valve plunger, said housing having an outlet port and a chamber from which substantially unrestricted communication is established to said port when said plunger is in one position, said chamber being in communication with said first source, said plunger being constructed to restrict communication between said port and chamber when the plunger is shifted to a second position to increase the pressure of fluid in said chamber, fluid actuated control means responsive to a differential in pressure between said chamber and port to control the flow of fluid in the second circuit from said second source to said motor, and means for supplying fluid from the first source to said control means at the pressure of the fluid in said chamber, and exhausting fluid from said control means at the pressure of the fluid in said port.

22. In a hydraulic actuator system, a fluid motor, fluid pressure generating means for supplying fluid to said motor to actuate said motor, a fluid circuit including a control valve connecting said fluid pressure generating means to said motor, said control valve including a housing and a valve member shiftable therein from a first position to a second position to control the flow of fluid from said pressure generating means to said motor, said housing having a pair of chambers therein for receiving fluid, said shiftable valve member having opposing surfaces, one of which is subject to the pressure of the fluid in one chamber and the

other of which is subject to the pressure of the fluid in the other chamber, means for supplying fluid from said pressure generating means to both of said chambers at equal pressure when the shiftable valve member is in one position for maintaining the valve member hydraulically in balance, means for shifting said valve member from the first position to the second position, said means including instrumentalities for rendering the means for supplying fluid to the chambers ineffective to supply fluid to one of said chambers while continuing the supply of fluid to the other of said chambers, and means for discharging the fluid from said one chamber at a predetermined rate to permit and time the movement of said valve member to the second position under the action of the fluid supplied to the other chamber.

23. In a hydraulic actuator system, a fluid motor, a first pump for supplying fluid at a rapid rate to said motor, a second pump for supplying fluid at a slower rate to said motor, fluid actuated control means reversely operable to render said second pump effective or ineffective, selectively, to supply fluid to the motor, a rapid traverse fluid circuit including a control valve through which the fluid flows toward the motor at the rapid rate from the first pump, said control valve having a first adjustment rendering said first pump effective to supply fluid to the motor to drive the motor in one direction, and a second adjustment rendering said first pump effective to supply fluid to the motor to drive the motor in an opposite direction, and means to supply fluid from said rapid traverse circuit under the control of said valve to said fluid actuated control means to impart movement thereto in one direction or in an opposite direction, selectively, upon selective adjustment of the rapid traverse control valve from the first position of adjustment toward the second position of adjustment, and reversely.

ERNEST J. SVENSON.

CERTIFICATE OF CORRECTION.

Patent No. 2,363,707.

November 28, 1944.

ERNEST J. SVENSON.

It is hereby certified that error appears in the printed specification of the above numbered patent requiring correction as follows: Page 5, second column, line 29, for "groves" read --grooves--; page 9, second column, line 8, claim 11, after "member" insert --for--; and that the said Letters Patent should be read with this correction therein that the same may conform to the record of the case in the Patent Office.

Signed and sealed this 29th day of May, A. D. 1945.

Leslie Frazer

Acting Commissioner of Patents.
